UNITED STATES PATENT OFFICE.

WILLIAM D. KELLY, OF LEWIS RUN, PENNSYLVANIA.

SCAFFOLD.

1,336,141.

Specification of Letters Patent.

Patented Apr. 6, 1920.

Application filed July 7, 1919. Serial No. 309,020.

To all whom it may concern:

Be it known that I, WILLIAM D. KELLY, a citizen of the United States, residing at Lewis Run, in the county of McKean and 5 State of Pennsylvania, have invented a new and useful Scaffold, of which the following is a specification.

This invention relates to scaffolds, and more particularly to portable scaffolds employed in connection with building chimneys 10 or the like.

The principal object of the present invention is to provide a scaffold which may be adjusted to conform to gable roofs of 15 various pitches.

A further object of the invention is to provide a scaffold, the elements forming the same being connected together to permit the same to be folded into a relatively small 20 bundle for transportation.

A still further object is the provision of a scaffold which may be supported on a roof without the employment of nails, bolts, or other securing means which might puncture 25 a roof.

With these and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without 35 departing from the spirit of the invention.

A practical embodiment of the invention, is shown in the accompanying drawing, in which:

Figure 1. illustrates a perspective view 40 of a scaffold constructed in accordance with my invention; and

Fig. 2. illustrates a view in elevation of the scaffold in its folded position.

Referring to the drawing in detail.

The numeral 1 indicates the legs of the 45 end sections each of which end sections includes the upper and lower connecting members 2 and 3, the same having connection with the legs 1 by the bolts 4 which as shown 50 pass through suitable registering openings provided in the connecting members 2 and 3 and legs 1.

Diagonally extending brace 5 connects the upper and lower connecting members 2 and 55 3 adjacent the ends thereof, thereby preventing lateral twisting of the side members

2 and 3 with relation to the legs 1. The end sections are connected at both sides thereof by the roof engaging members 6 and 7 which as shown have their ends 8 and 9 secured to the legs 1 adjacent the lower ends thereof by means of suitable bolts 10 passing through the legs 1 and members 6 and 7. The opposite ends of the members 6 and 7 are connected together as at 11 to permit of 60 adjustment of the members 6 and 7 to enable the angles thereof to be changed to embrace gable roofs of various pitches.

These end sections are also connected on both sides of the scaffold by the horizontal 70 upper and lower brace members 12 and 13, each of which is provided with an elongated slot 14 disposed adjacent the ends thereof.

The diagonally disposed side brace members 15 connect the horizontal brace members 12 and 13 and as shown, these brace members 12 and 13 are also provided with elongated slots 16, which slots accommodate 75 the securing bolts 17 which also extend through the elongated slots of the horizontal brace members 12 and 13 and connect the same to the end sections.

Suitable nuts 18 are provided on the bolts 17, for drawing the members 12, 13 and 15 80 together to prevent movement of one member with relation to the other, when the elements of the scaffold are adjusted to properly engage a particular gable roof.

From the foregoing it will be seen that 90 by removing the bolts 17, the side bracing members may be disconnected from the end sections, and readily folded into a compact bundle for transportation. When it becomes necessary to assemble the scaffold, the 95 angle of the gable roof on which the scaffold is to be mounted is measured, and the roof engaging members 6 and 7 correspondingly adjusted, the horizontal brace members 12 and 13 properly positioned and the 100 bolts 17 securing the ends thereof, tightened to bind the elements together to prevent movement of one member with relation to the other.

When the scaffold is assembled, the upper 105 brace members 12, together with the upper connecting members 2 provide suitable support for a platform not shown which platform may be of any suitable boards laid thereon.

What is claimed is:

A portable scaffold including rigid end

sections, roof engaging members having one of their respective ends pivotally connected to the lower ends of the end sections, the opposite ends of the roof engaging members being pivotally connected together to permit adjustment of the members to various angles, a plurality of horizontal brace members on opposite sides of the scaffold connecting said end members, diagonal members also connecting the corresponding end members, said horizontal members and diagonal members having slots, bolts operating in the slots to secure the roof engag-

ing members in their positions of adjustment, and means operating on one end of 15 each of the bolts for securing the end sections and roof engaging members in various positions of adjustment.

In testimony that I claim the foregoing as my own, I have hereto affixed my signature in the presence of two witnesses.

WILLIAM D. KELLY.
